UNITED STATES PATENT OFFICE.

FRED M. RICHEY AND FREDERICK McQUISTON, OF PITTSBURGH, PENNSYLVANIA.

BATHING DEVICE.

Application filed February 24, 1927. Serial No. 170,510.

This invention relates to a bathing device and is particularly adapted for use in bathing babies. Certain difficulties arise in the bathing of babies due to the necessity of handling the child with great care. These difficulties are accentuated by reason of the fact that ordinary bathing devices have not been disposed at a convenient elevation at which to handle the child. Certain other difficulties have arisen through lack of a suitable supporting device for holding the child during drying.

We provide a bathing device which obviates these difficulties by affording a tub of suitable dimensions disposed at a convenient elevation, and a drying table upon which the child may be placed during drying. The convenience of our device is increased by reason of its adjustability to meet particular local conditions. The device may be collapsed to fold into small dimensions when not in use.

In the accompanying drawings illustrating the present preferred embodiment of our invention,

Fig. 1 is a front elevation of the device opened for use.

Fig. 2 is a side elevation of the device shown in Fig. 1.

Fig. 3 is a sectional view on the line III—III of Fig. 1 to enlarged scale.

Fig. 4 is a sectional view on the line IV—IV of Fig. 3.

Fig. 5 is a sectional view on the line V—V of Fig. 3.

Fig. 6 is a plan view partly broken away, showing the construction of the drying table.

Fig. 7 is a side elevation of the table shown in Fig. 6.

Fig. 8 is a section on the line VIII—VIII of Fig. 7.

Fig. 9 shows a side elevation, partly broken away, of a guard for the drying table.

Fig. 10 is an end elevation of the guard shown in Fig. 9; and

Fig. 11 is a detail view of the locking means for holding the tub in operative position.

Referring to the illustrated embodiment (Figs. 1 and 2) there is shown a bathing device comprising a stationary frame 2 having a tub 3 mounted therein. The tub 3 is made of water proof fabric so as to be

collapsible and is mounted upon a framework 4 adapted to move from the horizontal position illustrated to an upright position indicated at 4'. The side bars 4^a of the framework 4 slide upon rollers 5 pivoted on the stationary frame 2. The end of the movable frame 4 adjacent the stationary frame 2 is constrained to move along guide rods 6 lying substantially vertically on the frame 2, the movable frame 4 being provided with rollers 7 (Fig. 5) which engage the opposite faces of the guide rods 6.

The tub 3 is maintained in horizontal position by gravity, the supporting rollers 5 being disposed considerably closer to the guided end of the frame 4 than to the free end thereof, so that the frame fulcrums about the rollers 5 and bears upwardly against stops 8 (Fig. 3, Fig. 11) at the upper end of the guide rods 6. In order to obviate any possibility of the tub collapsing and falling into an upright position, we provide a pair of locking pins 9 which protrude through the stationary frame 2 and engage extensions 9^a to the side bars 4^a. As shown in Fig. 11, locking pins 9 are normally urged toward the movable frame by means of a spring 6^a operating between a collar on the pin 9 and a plate 10 by which the locking pin assembly is mounted on the frame 2. The upper edge 9^b of the extension 9^a is beveled to push the pin to one side as the tub frame 4 is swung into horizontal position. The springs 6^a act to move the pins 6 into suitable receiving holes 9^c in the extension 9^a when the frame 4 is horizontal.

The tub 3 is preferably formed of waterproofed cloth, but may obviously be constructed of any suitable flexible material capable of being collapsed into a relatively small space. A drain 3^a facilitates emptying of the tub.

A drying table 11 is movably mounted in the stationary frame 2 so that the table may be swung into horizontal position (Figs. 1 and 2) above the tub 3. The drying table comprises a framework 12, formed of metal or wood, adapted to tightly engage a fabric head 13 and hold the same taut. The fabric head 13 which may be light canvas, is cut at the corners, indicated at 13^a, to insure a smooth fit when the head is drawn tight. The head 13 is strained by pressing a close fitting inner frame 14 upwardly inside the

outer frame 12 by means of wing nuts 15 threaded on bolts 15^a. The bolts 15^a pass through the outer framework 12, and the wing nuts 15 engage angle pieces 16 which 5 rest upon the inner frame 14. The fabric head 13 is gripped between the outer frame 12 and the inner frame 14. Suitable wires 17 contained within a fold at the edge of the fabric hold the head against slipping. The 10 outer bent portions of the angle pieces 16 lie against the outer frame 12 so that the wing nuts 15 tend to swing the angle pieces upwardly as shown in Fig. 7.

The table 11 is mounted to slide upon rollers 19 (Fig. 3) which cooperate with a groove 20 within the outer frame 12 of the table. The rollers 19 are held in spaced relationship by links 21 which are pivotally held to the stationary frame 2 by means of 20 other links 22. The table 11, therefore, may slide freely relatively to the frame 2 during the transfer from a vertical to a horizontal position. The table is maintained from accidental displacement by means of straps 25 23 fastened to the inner frame 14, the straps being adapted to engage angle pieces 24 fastened to the stationary frame 2. As shown in Fig. 3, the table may be brought into horizontal position and drawn forward so that 30 the inner frame 14 rests upon the angle pieces 24 while the strap 23 engages the opposite side of said angle pieces. At the same time the remote end 25 of the table engages a cross bar 26 on the stationary 35 frame 2. This motion is permitted by reason of the pivotal mounting of the links 21 on the pivot links 22 and the cooperation of the rollers 19 with the grooves 20.

The table 11 is held in horizontal position 40 by reason of the supporting angle 24 being disposed a short distance from the end of the frame so that gravity holds the table. The supporting angles 24 act as fulcrums, while the remote end 25 presses upwardly 45 against a cross bar 26 on the frame 2.

In order to disengage the table and lower the same, the table (Fig. 3) is slid along the supports 24, while the rollers 19 move along the corresponding groove 20, a sufficient distance to permit the straps 23 to clear the angles 24. When this has been done, the table may be simply permitted to slide by gravity into a vertical position, the rollers 19 moving along the grooves 20.

As shown in Figs. 7 and 8, the table 11 may be covered with a sheet of wood 18, if desired. The drying table thus formed may be used in conjunction with an ordinary bathtub by removing screws 22^a (Fig. 3) 55 and taking the drying table entirely out of the stationary frame 2. The drying table with a flat surface forms a convenient platform which may be placed across an ordinary tub.

60 In order to prevent the child from falling

or rolling from the dressing or drying platform, we provide a guard which surrounds the platform. This guard comprises a collapsible frame formed by posts 27 pivoted to members 27^a adapted to lie on top of the 70 table 11, the posts being inter-connected by means of rods 28 and 29 which support fabric walls 30. The rods 28 terminate in eyes 28^a which surround rods 29, whereby the rods 28 are movable angularly with respect to the posts 27. The guard is held rigid by means of pins 31 which pass through the posts 27 and engage angularly bent ends 32 of the rods 28. By referring to Fig. 9, it will be seen that the pins 31 effectively prevent the framework from collapsing toward the right as viewed in the drawing. Collapsing toward the left is prevented by blocks 33 mounted on the frame 27^a. 75

Although the side walls of the guard are collapsible, the front and back walls 30^a are of fixed dimensions and represent plane surfaces whether the guard is upright or collapsed. The upper edge of the front wall 90 30^a is supported by rods 29 and the lower edge is held by rods 34 which pass through the members 27^a. 80

The side walls 30 of the guard are supported along the top by the rods 28, and are stretched out to the full height by rods 35 which are attached to the lower edge of the fabric and are arranged to slide freely between the posts 27. 85

Eye-bolts 36 are attached to the rear of the frame, these eye-bolts being adapted to slide along guide rods 37 which extend along the back of the frame 2 and curve over the top thereof to finally terminate in a top member 2^a of the stationary frame. 100 The guide rods 37 automatically position the guard correctly upon the table when the guard is pushed into contact with the table. In order to place the guard out of the way, the pins 31 are simply withdrawn and the framework collapsed toward the back of the table. 105 The whole guard may then be slid along the guide rods 37 into the dotted line position of Fig. 2. The guard is supported at the back of the frame 2 by means of a hook 38 which engages the cross member 34 of the guard frame, a suitable opening 39 being provided in the front wall to accommodate the hook. 110

In order to maintain the device in proper position, we provide hook-like rods 40 which pass through suitable clamping blocks 41 attached to the frame 2 by means of wing nuts 42. The rods 40 may be slid through the clamping blocks 41 to any desired position and may be maintained there by tightening the wing nuts 42. The rods 40 are braced at any desired angle by means of bracing rods 43 hinged to the hooked rods at 44 and attached to the frame 2 by means 115 120 125 130

of wing nuts 45, the wing nuts 45 being effective for clamping the ends of the rods 43 at any point along suitable guides 46 extending along the frame 2. As shown in 5 dotted lines in Fig. 2, the hook rods may be positioned to engage the edge of an ordinary bathtub when the bathing device is resting on the bottom thereof. The full lines in Fig. 2 show the rods 40 extended to act as a 10 brace against the floor when the bathing device is used apart from any article of furniture, or fixture.

A towel rack 47 is conveniently mounted on the side of the frame 2. Receptacles 48 15 and 49 mounted on opposite sides of the stationary frame 2 provide convenient places for depositing toilet articles out of reach of the child.

Thus we provide an improved bathing device adapted for bathing babies, and affording a tub of suitable dimensions and disposed at a convenient elevation. We further afford a bathing device provided with a drying table having a guard therearound 25 the table disposed adjacent the tub.

Further advantages accrue to our invention by reason of the provision of a collapsible bathing device capable of being folded to occupy a comparatively small space.

30 The bathing device is adapted for use in conjunction with a bathtub or the like, or may be used apart from such fixture. The sliding portions of our folding bathing device have been illustrated and described as equipped with rollers. This feature has been found desirable in that it makes for ease of operation and permits accurate alignment of the various parts.

While we have illustrated and described 40 the present preferred embodiment of our invention, it will be understood that the invention is not limited thereto, since the drying table, guard walls, and tub may be formed of various materials and the details 45 of construction may be varied from that described within the scope of the following claims:

We claim:

1. A bathing device including a tub, a 50 swingable support therefor, and guides slidably cooperating with the support and disposed in a plane intersecting the plane of movement of the support.

2. A bathing device including a tub, a 55 swingable frame therefor, guides for said frame slidably cooperating therewith and disposed in a plane intersecting the plane of movement of the frame, and means for locking the frame in a predetermined position.

3. A bathing device including a tub, a 60 movable frame to which the tub is attached, guides defining the motion of one side of the movable frame and disposed in a plane intersecting the plane of movement of the

frame, and means for locking the frame when the tub is in operative position.

4. A bathing device including a tub, a 70 movable frame to which the tub is attached, guides defining the motion of one side of the movable frame and disposed in a plane intersecting the plane of movement of the frame, means for locking the frame when the tub is in operative position, and bearing means adapted to support the frame.

5. A bathing device including a movable 75 frame for a tub, said frame being slidable and swingable from a substantially horizontal operative position to a substantially upright position.

6. A bathing device including a stationary frame, a tub, a support for said tub movable relatively to the stationary frame, and a drying table 80 slidable and swingable to a position over the tub.

7. A bathing device including a relatively 85 narrow upstanding frame, a tub secured to the frame and movable from a vertical position on the frame to a horizontal position at one side thereof, and adjustable foldable 90 bracing means extending under the tub when in horizontal position.

8. A bathing device including a relatively 95 narrow upstanding frame, a tub secured to the frame and movable from a vertical position on the frame to a horizontal position at one side thereof, adjustable bracing means extending under the tub when in horizontal position, said bracing means including hook-like rods adjustable with respect to said 100 frame, bracing means for said rods, and means for locking the rods and bracing means in fixed position.

9. A bathing device including a relatively 105 narrow frame, a tub and a drying table lying substantially face to face in the frame when in inoperative position, said tub and table being movable to horizontal positions, the one being disposed above the other.

10. A bathing device including a relatively 110 narrow frame, a tub, a drying table, said tub and drying table lying alongside one another in substantially parallel planes in the frame when in inoperative position and being movable to horizontal positions 115 wherein the one is disposed above the other, and a guard for the drying table.

11. In a bathing device having a drying 120 table, a collapsible guard for said table, said guard comprising substantially rigid spaced apart frame members, and fabric walls connecting the frame members.

12. In a bathing device, a stationary 125 frame, a drying table movable relatively thereto, guide means defining the motion of said movable table, and means cooperating with one side thereof only for holding the table in horizontal position.

13. In a bathing device, a stationary 130 frame, a tub, a supporting frame for said

- tub, the supporting frame being movable from substantially a vertical position to a substantially horizontal operative position, a plurality of guides constraining the motion of one side of the frame, rollers cooperating with the guides to define the motion of the frame, and bearing rollers adapted to guide the movable frame and support the same in horizontal position.
14. In a bathing device, a stationary frame, a tub, a supporting frame for said tub, the supporting frame being movable from substantially a vertical position to a substantially horizontal operative position, a plurality of guides constraining the motion of one side of the frame, rollers cooperating with the guides to define the motion of the frame, bearing rollers adapted to guide the movable frame and support the same in horizontal position, and means for locking the movable frame in horizontal position.
15. In a bathing device, a stationary frame, a drying table movable relatively thereto, and means defining the motion of said table, said means including a groove on the table, a plurality of spaced rollers adapted to cooperate with the groove, and a link pivoted to the stationary frame and pivotally supporting the spaced rollers.
16. In a bathing device having a drying table, a collapsible guard adapted for use with said table, the guard comprising a plurality of supporting posts pivoted to a frame, a plurality of rods connecting the posts, fabric walls supported by the connecting rods, and means holding the rods and posts in rigid relationship when the guard is in operative position.
17. For use with a bathing device, a drying table comprising a frame, a second frame insertable in the first mentioned frame, means for pressing the frames into mutual engagement, and a head adapted to be held between the frames and to form a table top.
18. In a bathing device having a stationary frame and a drying table, a collapsible guard adapted for use with said table, the guard comprising a plurality of supporting posts pivoted to the frame, a plurality of rods connecting the posts, fabric walls supported by the connecting rods, and means holding the rods and posts in substantially rigid relationship when the guard is in operative position, a plurality of guides on said stationary frame, and means cooperating with the guides to conform the motion of the
- guard thereto when the guard is moved from a position of cooperation with the drying table to an inoperative position on the stationary frame.
19. In a bathing device, a stationary frame, a drying table movable relatively thereto, means defining the motion of said table, said means including a groove on the table, a member adapted to cooperate with the groove, and a link pivoted to the stationary frame rotatable supporting the member which cooperates with the groove.
20. A bathing device comprising a frame having bathing means thereon, and bracing means connected to the frame and adapted to cooperate for bracing the same with a stationary support at various heights with respect to the frame.
21. A bathing device comprising a frame having bathing means thereon, and bracing means connected to the frame and adjustable to engage a stationary support at various heights with respect to the frame.
22. A bathing device comprising a frame having a tub and a drying table connected thereto, the tub and drying table lying substantially at the same height when in inoperative position and being movable respectively to operative positions at different heights.
23. A bathing device comprising a frame having a tub and a drying table connected thereto, the tub and drying table lying side by side at substantially the same height when in inoperative position and being movable respectively to operative positions one above the other.
24. In a bathing device, a frame, bathing means thereon, bracing means connected to the frame and extending outwardly therefrom, and means connected to the frames and to the bracing means whereby the position of the bracing means may be adjusted to enable such means to engage a desired support.
25. In a bathing device, a frame, bathing means thereon, a bracing arm connected to the frame and extending outwardly therefrom, and a link connected to the frame and to the arm intermediate its extremities and adjustable to vary the position of the arm with respect to the frame.
- In testimony we have hereunto set our hands.

FRED M. RICHEY.
FREDERICK McQUISTON.
